UNITED STATES PATENT OFFICE

136,877

DESIGN FOR A CONTAINER FOR A DEODORANT

Joseph H. Estes, New York, N. Y.

Application August 28, 1943, Serial No. 111,009

Term of patent 14 years

To all whom it may concern:

Be it known that I, Joseph H. Estes, a citizen of the United States and a resident of the city, county, and State of New York, have invented a new, original, and ornamental Design for a Container for a Deodorant, of which the following is a specification, reference being had to the accompanying drawing, forming a part thereof.

Fig. 1 is a front view of a container for a deodorant showing my new design.

Fig. 2 is a side view thereof.

Fig. 3 is a top view thereof.

Fig. 4 is a perspective view of the container shown in Figs. 1, 2 and 3.

I claim:

The ornamental design for a container for a deodorant, substantially as shown.

JOSEPH H. ESTES.
